INVENTOR
ERNSTALD H. YOUNGE
BY
C. F. Blake
ATTORNEY

UNITED STATES PATENT OFFICE.

ERNWALD H. YOUNGE, OF PORTLAND, OREGON.

STEREOPTICON.

1,366,443.

Specification of Letters Patent. Patented Jan. 25, 1921.

Application filed April 19, 1919. Serial No. 291,407.

To all whom it may concern:

Be it known that I, ERNWALD H. YOUNGE, a citizen of the United States, residing at Portland, county of Multnomah, State of Oregon, have invented certain new and useful Improvements in Stereopticons, of which the following is a specification.

My invention relates to stereopticons in general, and particularly to such as are used 10 for displaying advertising purposes, and the object of my invention is to provide means to display upon a screen, billboard or building at night a continuous moving series of advertisements.

I accomplish the above object by means 15 of the construction illustrated in the accompanying drawing, which is a part of this application for Letters Patent, like characters of reference indicating like parts 20 throughout the several views thereof, and in which:

Figure 1 is a plan view of my device, the cover being removed therefrom.

Fig. 2 is a side elevation of my device, 25 parts being broken away to illustrate the construction.

Fig. 3 is a perspective detail of the film 30 steadyng device.

Fig. 4 is a perspective detail of the friction arm.

Fig. 5 is a detail of one of the film rollers.

In general my device consists of the regular stereopticon projecting and condensing lenses and light box, combined with an endless film, a film steadyng device between the lenses, means to actuate the film, and means whereby any desired length of film 35 may be used.

The arrangement of the projecting lens 40 6, the condensing lens 7 and light box 8 are the same as usually used in stereopticons, and the film 9 is transversely moved across the field of said lenses between the same.

To contain the film I provide a box 10 45 having forwardly extending arms 11, one arm upon either side of the light box 8 and condensing lens 7, as shown in Fig. 1. Within the forward end of each of said arms 11 I mount a roller 12, between which rollers 50 the film 9 is stretched across the field of the lenses. From each roller 12 the film extends to the rearward through the respective arm 11 into box 10, wherein it is wound around a plurality of rollers 12^a similar to rollers 12. All said rollers are mounted 55 upon pins 13 secured to the bottom of said

box 10 or to the arms 11 thereof respectively, by nuts 14, as shown in detail in Fig. 5.

To provide means for accommodating 60 various lengths of film a plurality of holes 15 are disposed in the bottom of box 10, thus allowing the rolls 12^a to be disposed suitably for the desired length of film, as shown in dotted lines in Fig. 1.

To actuate said film 9 I provide therefor a roller 16 similar to rollers 12 and 12^a, but secured to a shaft 17, upon which shaft is mounted a worm gear 18, said worm gear being driven by a motor 19 through a pinion 20, gear 21 and worm 22, as shown in Fig. 1.

To secure sufficient friction between the film 9 and driving roller 16 I provide an arm 23 pivotally mounted within box 10 and 75 having upon the free end thereof a roller 24, and a spring 25 adapted to keep roller 24 in firm contact with the film 9 as it passes over roller 16, as shown in Fig. 1, and in detail in Fig. 4.

To preserve that portion of film 9 upon which the advertising matter appears from damage, all the various rollers are formed with central depressions 26 between enlarged heads 27, with which heads the edge portions of the film contacts, and flanges 28 to 80 keep the film upon the rollers.

To keep the film 9 steady and vibrationless as it passes through the field of the lenses, I provide a steadyng device illustrated in detail in Fig. 3. This device consists of a lower plate 29, and two upper plates 30 supported from plate 29 by columns or posts 31, a slot 32 being left between the adjacent edges of plates 30, into 95 which slot the film 9 is inserted.

The adjacent faces of plates 29 and 30 are spaced apart exactly the width of the film 9, and keepers 33 are provided at each end of plates 30 disposed to keep the inserted film 100 between the plate 29 and the keepers 33, so that once inserted into slot 32 the film cannot escape therefrom in operation.

The keepers 33 are each pivotally mounted upon one of plates 30, preferably upon 105 the top of the respective post 31, and adapted to snap over the top of the adjacent post 31 to secure the respective keeper in place after the film has been inserted into slot 32. By this construction the keepers may be rotated or opened to permit of inserting the film into slot 32. To steady the film 9 as

it passes through this device in the field of the lenses I provide downwardly projecting rollers 34 mounted upon plates 30 respectively, and upwardly projecting rollers 35 mounted upon plate 29.

Said rollers 34 and 35 are respectively in such close peripheral juxtaposition as to each contact with the film 9 when it is inserted therebetween, and thus to hold said 10 film steady and vibrationless as it passes along.

Said rollers 34 and 35 extend from their respective plates 30 and 29 only a sufficient distance to contact with a narrow portion 15 of the edge of the film, leaving that portion thereof bearing the advertising matter unobstructed as it passes through the field of the lenses.

By means of this construction any desired length of the film may be inserted and 20 operated in my device, and the various advertisements thereon successively projected upon the screen, the operation being continuous.

My invention may be made of any size, and constructed of any materials deemed 25 convenient and suitable for a device of this character, and while I have illustrated and described a form of construction and arrangement of parts found desirable in materializing my invention, I wish to include 30 in this application for Letters Patent all mechanical equivalents and substitutes that may fairly be considered to come within the 35 scope and purview of my invention as defined in the appended claims.

Having disclosed my invention so that others may be enabled to construct and to use the same, what I claim as new and desire to secure by Letters Patent is:

1. A stereopticon in combination with an endless film; a box rearwardly disposed to said stereopticon adapted to contain a portion of said film; arms upon said box for-

wardly extending upon either side of said 45 stereopticon and adapted to contain a portion of said film; rollers in the forward ends of said arms adapted to have a portion of said film stretched therebetween through the field of said stereopticon; adjustably positioned rollers within said box adapted to have a portion of said film stretched therebetween; and means to operate said film.

2. In a stereopticon having means for continuously passing a film through the field thereof; a film steady device consisting of a lower plate; a pair of upper plates supported therefrom, and having their adjacent edges slightly separated; keepers upon said upper plates adapted to open to allow said film to be inserted between said plates, and to be then closed to keep said film thus inserted; and rollers mounted upon said lower and said upper plates adapted to hold said film vibrationless as it passes therebetween.

3. A stereopticon in combination with a film containing box disposed rearwardly of said stereopticon; forwardly projecting parallel arms upon said box embracing said stereopticon and having oppositely disposed vertical slots in the inner sides of said arms adjacent the ends thereof; rollers within the extremities of said arms adjacent said slots adapted to receive thereon a film passing through said slots from arm to arm within the field of said stereopticon; rollers within said box adapted to receive said film thereon; and means to propel said film.

In witness whereof I claim the foregoing as my own, I hereunto affix my signature in the presence of two subscribing witnesses, at Portland, county of Multnomah, State of Oregon, this 9th day of April, 1919.

ERNWALD H. YOUNGE.
